BELT ATTACHING GUN CRADLE

Oscar L. Ulvang, Duluth, Minn.

Application April 21, 1949, Serial No. 2,170

Term of patent 3½ years

(Cl. D30—1)

To all whom it may concern:

Be it known that I, Oscar L. Ulvang, a citizen of the United States of America, residing at Duluth, in the county of St. Louis and State of Minnesota, have invented a new, original, and ornamental Design for a Belt Attaching Gun Cradle, of which the following is a specification, reference being had to the accompanying drawing, forming a part thereof.

In the drawing:

Fig. 1 is a side elevational view of a belt attaching gun cradle, showing my new design.

Fig. 2 is a rear elevational view of Fig. 1.

Fig. 3 is a top plan view of Fig. 1.

Fig. 4 is a front elevational view of Fig. 1.

I claim:

The ornamental design for a belt attaching gun cradle, as shown.

OSCAR L. ULVANG.
